P. R. DIXON

GAS BURNER

Filed Aug. 27, 1921

By

G. M. Talbert

Attorney

UNITED STATES PATENT OFFICE.

PHILIP R. DIXON, OF CINCINNATI, OHIO.

GAS BURNER.

Application filed August 27, 1921. Serial No. 495,853.

To all whom it may concern:

Be it known that PHILIP R. DIXON, a citizen of the United States of America, residing at Cincinnati, in the county of Hamilton and State of Ohio, has invented new and useful Improvements in Gas Burners, of which the following is a specification.

The object of the invention is to provide a gas burner for use in connection with stoves, boiler furnaces, and the like whereby a more complete and approximately perfect combustion of the fuel and therefore economy in the use thereof may be secured than is possible with the commercial types of burners and more particularly to provide a burner wherein a thorough mixing of the gas or fuel and air induced by an expansion thereof and therefore an increased activity of relative movement of the elements thereof may be secured due to the heat of the combustion at the burner, to which the fuel and gas are subjected in their approach to the combustion point without diverting the heat due to such combustion from the purpose for which it is primarily intended and hence without detracting from the efficiency of the burner as a heating agent; and with this object in view the invention consists in a construction and combination of parts of which a preferred embodiment is shown in the accompanying drawings, wherein:

Figure 1 is a plan view of a burner constructed in accordance with the invention and suitable for use in connection with a cook stove or range.

Figure 2 is a side view partly in section of the same.

Figure 3 is a side view of a modified form of the burner adapted more particularly for use in connection with boiler furnaces, the same being shown partly in section.

The burner consists essentially of a burner head or tip 10 which in the construction illustrated in Figures 1 and 2 is of substantially flat horizontal form having a plurality of burner orifices 11 and a mixing tube 12 in communication with the burner tip or head and arranged in the path of the flame and heat generated at the outer burner orifices so as to be maintained at a relatively high temperature to cause an expansion of the gas and air passing therethrough in its path to the burner head or tip, said

mixing tube being in position to receive gas from the supply pipe 13 having a suitable cut-off valve 14 and being open for the induction of air under the control of a suitable register 15.

The exposure of the mixture of gas and air to the heat of the burner head or tip not only predisposes the mixture to better combustion by reason of the high temperature thereof but causes a more rapid molecular movement of the gas and air in the passage thereof through the mixing tube so that a more intimate mixture thereof is secured, such increased rapidity of molecular movement being incident to the expansion thereof, and consequently when the mixture reaches the combustion point and is ignited the maximum efficiency is secured.

In the construction illustrated in Figure 3 the mixing tube 17 is correspondingly arranged in the path of the heat at the combustion point represented by the outlet end of the burner tube 18 which is entered by the outlet end of the mixing tube and is open at its outer end, outside of the wall 19 of the furnace to enable the operator to observe the condition of the flame, the exposed outer portion of the mixing tube being protected by a shield 20 to prevent wasteful radiation of heat therefrom and the portion of the mixing tube within the furnace being suitably protected from the direct contact of the flame by a suitable shield 21 of fire clay or its equivalent while being subject to heat of a degree sufficient to effect the expansion and hence efficient mixture of the gas and air of which the former is introduced into the mixing tube by the gas supply pipe 22 fitted with the controlling valve 23. The air as in the other form of the invention is admitted at 24 by induction.

Having described the invention, what is claimed as new and useful is:

A gas burner having a burner head provided with a plurality of burner orifices, and a mixing tube disposed above the head and arranged in a plurality of convolutions of which the lowermost connects with the head, said convolutions being disposed in encircling relation with the head and just above the plane of the latter.

In testimony whereof he affixes his signature.

PHILIP R. DIXON.
